UNITED STATES PATENT OFFICE.

ELMER V. HILLBURG, OF MCKEES ROCKS, PENNSYLVANIA.

LOCKING MEANS FOR GEAR-SHIFTING LEVERS.

Application filed November 13, 1920. Serial No. 423,938.

To all whom it may concern:

Be it known that I, ELMER V. HILLBURG, a citizen of the United States, residing at McKees Rocks, in the county of Allegheny and State of Pennsylvania, have invented certain new and useful Improvements in Locking Means for Gear-Shifting Levers, of which the following is a specification, reference being had to the accompanying drawings.

This invention relates to means for locking automobiles, and particularly that class of locks wherein the gear shifting lever is locked from operative engagement with the gears.

The general object of my invention is to provide a very simple lock of this character which may be cheaply made, which may be readily installed, and which is thoroughly effective in practice.

A further object is to provide a lock of this character which may be adapted to many different makes of cars, and wherein the gear shifting lever is provided with a locking section forming a part of the lever, which in one position operatively connects the lever with the yokes of the gear shifting rods, and which in another position locks these yokes so that the gear shifting rods are held from any movement.

A further object in this connection is to so mount this shiftable section in the handle section of the lever that the shiftable section, when in its locking position, is disposed so that no means can be used for prying up the shiftable section out of its locking position, and whereby no point is presented to break the lock or disengage the shiftable section from its operative and locking position.

Other objects will appear in the course of the following description.

My invention is illustrated in the accompanying drawings, wherein:

Figure 1 is a longitudinal sectional view of a gear locking and operating lever constructed in accordance with my invention;

Figure 2 is a fragmentary section on the line 2—2 of Figure 1;

Figure 3 is a section on the line 3—3 of Figure 2;

Figure 4 is a vertical sectional view on the line 4—4 of Figure 2;

Figure 5 is a fragmentary vertical section of the upper portion of the lever body showing the locking section depressed;

Figure 6 is a sectional view on the line

6—6 of Figure 1 looking in the direction of the arrows;

Figure 7 is a sectional view on the line 7—7 of Figure 1 looking toward the yokes;

Referring to these drawings, it will be seen that the gear shifting lever 10 is of usual or conventional form. This gear shifting lever has a relatively straight body portion and a handle portion 11, this handle portion in the embodiment illustrated extending upward at an inclination to the body portion, but the handle portion might extend straight upward in line with the body portion, it being sufficient that the handle portion be off-set with relation to the body portion.

The body portion of the gear shifting lever is longitudinally bored, the lower portion of this bore being of increased diameter, as at 12, and the upper portion of the bore at its upper end being formed

to provide a relatively deep recess 13. Operating within this bore is the shiftable or locking section 14. The lower portion of this section 14 has a diameter equal to

the enlarged diameter of the bore, the upper portion being reduced to fit the upper portion of the bore, thereby providing a shoulder 15 which normally bears against the shoulder 12. The upper end of this rod or section 14 is formed with a head 16, while the

lower extremity of this rod or section 14 is formed to provide a globular head 17 and above this globular head and spaced therefrom is a portion 18 which is rectangular in cross section. The rod 14 between the shoulder 15 and the head 16 at two points is formed with ratchet recesses 19 and 20.

Surrounding the upper end of the section 14 is a coiled compression spring 21, which at its upper end bears against the under side of the head 16 and which at its lower end bears against the bottom of the recess 13. This spring urges the

section 14 to a raised position, and in this position the globular head 17 is disposed between the two yokes 22 and 23 which are connected to the usual gear shifting rods 24. These yokes 22 and 23 and the rods 24

are those ordinarily found on automobiles for the purpose of shifting the gears. The gear shifting lever is mounted in the usual manner upon a ball 25 which is shown as having a central passage for the passage of

the body of the lever and having the lever pinned thereto, this ball 25 resting in the

usual socket 26 of a base 27 so that the lever is universally supported and may move forward or backward or laterally in either direction. This is the usual and common 5 means for supporting a gear shifting lever and forms no specific portion of my invention.

The body of the lever 10 above its point of connection with the ball 25 is formed with 10 the usual bell-shaped housing cap 28. This, as illustrated, is formed with an upstanding collar 29 at its upper end. This is pinned upon a two-part collar 30 which is disposed between the annular shoulders 31 formed on 15 the body 10. This bell-shaped cover or cap 28 extends over the housing 27 and is approximately concentric thereto and to the ball 25 but permits the lever to be shifted to any of its four positions.

20 For the purpose of locking the shiftable section 14 of the lever in its depressed and gear locking position, I form a lock chamber 32 in the body 10 to one side of the bore, through which the section 14 passes, and 25 dispose therein the lock casing 33 which may be any suitable character and which is shown as including a rotatable key actuated barrel 34 of ordinary type. The inner extremity of this barrel carries a plate 30 35 formed with a notch 36, and swingingly mounted within the recess 32 is a pawl 37. This pawl is pivotally mounted at its upper end on a pin 38 and at its lower end has a pin 39 which engages with the notch 36. 35 The pawl is provided with a tooth 40, which tooth is engageable with the ratchet recesses 19 and 20. A spring may be used to urge this pawl outward to its locking position.

Normally the section 14 is raised relative 40 to the body 10 by means of the spring 21, and under these circumstances the tooth 40 of the pawl engages the recess 20 of the rod 14, thus locking the body section and the locking section together against upward 45 movement of the locking section. At this time, the globular head 17 is disposed in a neutral position between the yokes 22 and 23, and the lever will operate in the usual manner to shift the gears by shifting the lever laterally either into engagement with the yoke 22 or into engagement with the yoke 23 and then shifting the lever forward or rearward to shift the selected yoke. When it is desired to lock the machine, however, 55 the locking section 14 is depressed against the action of the spring 21 and this carries the head 17 out of its position between the yokes and shifts the rectangular locking head 18 into position between the yokes. This locking head 18 has bevelled 60 side faces and when they engage between the yokes they wedge the yokes apart, fit in the space between the forks of the yokes, and, of course, under these circumstances it 65 is impossible to shift the lever longitudi-

nally or laterally, as it is impossible with the ordinary gear shifting mechanism of an automobile to shift both these yokes at the same time. When the locking section 14 is depressed, the pawl will spring into the 70 notch 19 and lock the locking section 14 in its depressed and locking position. Thereafter it is impossible to release the locking section to permit it to shift upward to its unlocked position except by inserting a key 75 within the keyhole of the barrel 34, rotating this barrel, and releasing thereby the tooth 40 of the pawl from its engagement with the notch 20. As soon as this has been done, the spring 21 acts to raise the locking section of 80 the lever to its normal position, when the ball 17 is once more disposed between the yokes in position to engage the yokes in the usual manner.

It is to be particularly noted that the head 85 16, when the section 14 is depressed, is entirely disposed within the socket or recess 13 and fits the same closely so that there is no projection of this head 16 which would permit any implement to be inserted to pry 90 up the head and break the pawl 37. The lock casing 33 is pressed into its place in the recess 32 and the face of the lock casing is flush with the face of the body of the lever so that it is impossible to remove this lock 95 casing. Furthermore, the lock casing may be pinned in place against movement or otherwise so engaged with its recess or socket as to be incapable of removal.

It will be seen that under normal circumstances the lever operates precisely the same as any ordinary gear shifting lever, but that when the locking section 14 is depressed, it will lock the gears against any shifting movement and will lock the lever against 100 any shifting movement, thus rendering the automobile inoperative until the locking section is again released and moves upward.

The lever body and the locking section will be formed of steel drop forgings and, 105 of course, the body of the lever section may be nickel-plated or otherwise finished. There will be two pins holding the bell in place, one of these pins being smooth and extending through the body and the collar 110 section 30, and the other being screw-threaded and extending through the collar 29, the collar section 30 and into a longitudinally extending slot 41 formed in the locking section 14, thus holding the locking section 115 from any turning movement. This screw-threaded pin, after it is inserted, may have its shank broken off so as to make it impossible to remove this screw-threaded pin. The lock casing 33 will be pressed into the 120 recess 32 and then held within this recess by a screw pin forced into place and then twisted off, the nickel-plating which covers the lever body being carried over this broken-off end of the screw pin so as to entirely fill 125 130

the opening in the wall of the recess and prevent any possible removal of this pin. Thus it is impossible to remove the lock and impossible to remove the bell so as to detach the lever from its engagement with the gears. It is pointed out that in this construction the lever of the locking section or plunger is disposed in such position that it will not be accidentally shifted while the locking lever is being manipulated. In other words, it is not disposed adjacent the hand engaging end of the handle portion of the lever but is disposed a considerable distance below this hand engaging end where it is entirely out of the way and, as before remarked, in such position as to render it impossible to operate it accidentally. This is of considerable advantage, inasmuch as if the locking section had its head disposed at the handle end of the lever, the locking section might be shifted just as it was attempted to shift the gears and the gears would thus be either broken off or a serious accident might occur from a failure to shift gears at the proper moment by reason of the gears being locked. Furthermore, by putting the locking section low down upon the locking lever, the locking lever is made stronger than it otherwise would be. It is to avoid the chance of locking the gears when attempting to shift the gears that I have made the locking lever in two sections, only one of which is depressible, this section being so disposed that it cannot be accidentally shifted when the lever is being manipulated.

While I have illustrated one particular form of my invention which is particularly adapted to certain types of cars, it will be understood that the construction might be modified to suit other types of cars without departing in any way from the spirit of the invention.

I claim:—

1. A gear shifting lever for automobiles comprising a section mounted for swinging, gear-selecting and gear-shifting movement, a second section slidably mounted on the first named section for longitudinal movement and extending below it and having upon it a gear-yoke operating head and a gear-yoke locking head, said heads being longitudinally separated and key actuated means for locking the sliding section with its gear-yoke locking head in operative position.

2. A gear shifting lever for automobiles comprising a section mounted for swinging, gear-selecting and shifting movement, a second section slidably mounted within the first named section for longitudinal movement and extending below it and having a gear-yoke operating head and a gear-yoke locking head, said heads being longitudinally separated the last named head be-

ing rectangular, and means carried by the first named section for locking the sliding section with its gear-yoke locking head in operative position.

3. A gear shifting lever for automobiles comprising a body section mounted for swinging, gear-selecting and gear-shifting movement, said body section having a bore extending longitudinally through it from its lower end, the bore opening at its upper end below the upper extremity of the body section, a second section slidably mounted in said bore for longitudinal movement and extending below the body section and having at its lower end a gear-yoke operating head and a gear-yoke locking head, said heads being longitudinally separated a spring normally urging the second named section into a position with its gear-yoke operating head in operative position, and key actuated means carried upon the body section for locking the sliding section with its gear-yoke locking head in operative position.

4. A gear shifting lever for automobiles comprising a body section mounted for swinging, gear-selecting and gear-shifting movement, said body section having a bore extending longitudinally through it from its lower end, the bore opening at its upper end below the upper extremity of the body section, a second section slidably mounted in said bore for longitudinal movement and extending below the body section and having at its lower end a gear-yoke operating head and a gear-yoke locking head, said heads being longitudinally separated, a spring normally urging the second named section into a position with its gear-yoke operating head in operative position, a lock casing carried upon the body section, the body section being recessed to receive said casing, a pawl disposed in the recess, the second named section having a notch to receive said pawl when the second named section is depressed with its gear-yoke locking head in operative position, and key actuated locking means carried in the lock casing for actuating said pawl.

5. A gear shifting lever for automobiles comprising a body section mounted for swinging, gear-selecting and gear-shifting movement, said body section having a bore extending longitudinally through it from its lower end, the bore opening at its upper end below the upper extremity of the body section, a second section slidably mounted in said bore for longitudinal movement and extending below the body section and having at its lower end a gear-yoke operating head and a gear-yoke locking head, said heads being longitudinally separated a spring normally urging the second named section into a position with its gear-yoke operating head in operative position, a lock casing carried upon the body section, the

body section being recessed to receive said casing, a spring actuated pawl disposed in the recess, the second named section having a notch to receive said pawl when the second named section is depressed with its gear-yoke locking head in operative position, and key actuated means for retracting said pawl.

6. A gear shifting lever for automobiles comprising a body section mounted for 10 swinging, gear-selecting and gear-shifting movement, this body section having a longitudinally extending bore, the upper portion of the bore being smaller in diameter than the lower portion and said bore extending 15 from the lower end of the body section to a point midway between its upper and lower ends and the body section being formed with a lock-receiving recess intersecting said bore, a longitudinally extending second section 20 slidingly mounted in the bore of the first named section for longitudinal movement and having its upper end reduced in diameter relative to its lower portion, said second named section extending below the 25 body section and having a gear-yoke operating head at its lower extremity and a gear-yoke locking head disposed above the operating head, a spring normally urging the second named section upward to bring the gear-yoke operating head into operative position, a lock casing disposed in said recess of the body section, a key actuated rotatable barrel in the lock casing, and a spring actuated pawl coacting with the barrel, the 30 second named section being provided with notches with which said pawl engages when the second named section is in its fully raised or fully depressed positions.

7. A gear shifting lever for automobiles 40 comprising a body section mounted for swinging, gear-selecting and gear-shifting movement and formed with a bore extending longitudinally from the lower end of the body section to a point midway between its ends, the upper portion of said bore being of smaller diameter than the lower portion, the body section having a lock casing recess intersecting the bore, the upper extremity of the bore being enlarged, a second section disposed within the bore of the first named section for longitudinal movement and having its upper portion of smaller diameter than its lower portion, the second section projecting below the body section and having a gear-yoke operating head at its lower extremity and a gear-yoke locking head disposed above the operating head, said second section at its upper end having a head movable into the enlargement 50 of the upper portion of the bore, a spring disposed in said enlargement and bearing against the head and urging the second section upward, the second named section having notches in its side face, a locking member shiftably mounted within the lock casing.

8. A gear shifting lever for automobiles 70 comprising a section mounted for swinging gear selecting and gear shifting movement, a second section slidably mounted on the first named section and extending below it and having upon it a gear-yoke operating head and a gear-yoke locking head, the second section being shiftable to bring either of said heads in a gear-yoke engaging position.

9. In an automobile, the combination with 80 a support having a semi-spherical socket and opposed gear-shifting yokes, of a lever for shifting said yokes comprising a body section having a globular supporting member resting in said socket, the body section having a handle at its upper end and being formed with a longitudinally extending bore, a second section mounted within the longitudinally extending bore of the first 85 named section and normally projecting beyond said bore at its upper end, the lower end of the second named section being formed with a globular yoke engaging head and above this head with a rectangular yoke locking head, said second named section being provided with notches in its side faces, a key actuating lock device mounted upon the body section and including a member shiftable into or out of the notches, a spring urging said second named section upwardly 90 with relation to the body section, and a bell-shaped housing carried upon the body member and extending over the support therefor and over the said socket therein.

10. In an automobile, the combination with 105 a support having a semi-spherical socket and opposed gear-shifting yokes, of a lever for shifting said yokes comprising a body section having a globular supporting member resting in said socket, the body section having a handle at its upper end and being formed with a longitudinally extending bore, a second section mounted within the longitudinally extending bore of the first named section and normally projecting 110 beyond said bore at its upper end, the lower end of the second named section being formed with a globular yoke engaging head and above this head with a rectangular yoke-locking head, said second named section being provided with notches in its side faces, a key actuated locking device mounted upon the body section and including a member shiftable into and out of the notches, a spring urging said second named section 115 upwardly with relation to the body section, and a bell-shaped housing carried upon the body section and extending over the support therefor and over the said socket therein, said bell-shaped housing 120

130

having a collar at its upper end; a collar immediately surrounding the body member opposite the collar on the bell-shaped housing, said body member being formed with 5 upper and lower annular flanges bearing against the upper and lower faces of the second named lower collar, and pins extending through the collars and into said body section, one of said pins projecting through 10 the said body section, and the second named section having a groove in which said pin projects.

11. In an automobile, the combination with a pair of gear-shifting yokes, of a gear- 15 shifting lever comprising a body section, a support upon which said body section is mounted for swinging movement in a plurality of directions, a second section slidably mounted in the first named section 20 for rectilinear movement and extending below the first named section and having on its lower extremity a globular yoke-engaging head and above this head having a rectangular yoke-locking head, a spring 25 urging the second named section upward to bring its globular head opposite said yokes, and key actuated means for locking the second named section with its yoke-locking head opposite said yokes.

30 12. A gear shifting lever for automobiles including a body member mounted for gear shifting movement and having a handle end, a rectilinearly movable gear-yoke engaging member mounted within the body member 35 for longitudinal movement and having its upper end normally projecting from and beyond the body from below the handle end thereof, the lower end of the gear-yoke engaging member having thereon a gear-yoke

operating head and a gear-yoke locking 40 head, said heads being longitudinally separated and means carried by the body member and coacting with and locking the gear-yoke engaging member with its operating head in engagement with the gear-yoke or 45 its locking head in engagement with the gear-yoke.

13. A gear shifting lever for automobiles comprising a section mounted for swinging gear selecting and gear shifting movement 50 and having a handle, a second section longitudinally slidable on the first named section and extending below it and having upon it a gear-yoke operating head and a gear-yoke locking head, said heads being longitudinally spaced from each other and means for locking the sliding section with its gear-yoke locking head in operative position. 55

14. A gear shifting lever for automobiles comprising a section mounted for swinging gear selecting and gear shifting movement, 60 a second section longitudinally slidable on the first named section and extending below it and having upon it a gear-yoke operating head and a gear-yoke locking head, and a releasable latch adapted to hold the second named section from upward movement when either the operating head or the locking head is in engagement with the yoke. 65

15. A gear shifting lever for automobiles 70 having thereon a gear-yoke operating head and a gear-yoke locking head, and means for shifting either one of said heads into operative position with relation to a gear-yoke.

In testimony whereof I hereunto affix my 75 signature.

ELMER V. HILLBURG.
